Des. 1676

John B. Chagois of New York, N.Y.
Letters Patent No 1676 - Dated Decr 9, 1862.

The schedule referred to in these Letters Patent and making part of the same.

To all whom it may concern:

Be it known that I, John B. Chagois, of 261
Bleecker St, in the City, County and State of New York, have invented
a new Design for a Trade Mark for Medicine termed "Chagois"
Elixir; and I do hereby declare that the following is a full clear
and exact description of the same reference being had to the accom-
panying drawing making a part of this specification.

This design is intended to be printed
upon labels for the bottles in which the medicine is to be put up or
for the packages which contain the bottles or to be printed upon the
packages themselves.

In the centre of the design is a small picture.

Des. 1676

representing a sick man reclining on a bank in the shade of a tree, and a physician holding a bottle from which he is about to administer medicine to the sick man, holding the bottle up to his mouth.

This picture is surrounded by an oval border a, which is surmounted by an eagle holding in his beak a ribbon on which are inscribed the words "Chargois' Elixir." On opposite sides of the border a, there are two scrolls b, and c, on which are inscriptions in French and English or other languages setting forth for what disorders the Elixir is a remedy, the said scrolls having ornamental borders of scroll work and foliage. The central picture, the Eagle and the scrolls are surrounded by a double border d, e, the exterior d, of which is plain and the interior e, embellished with ornamental leaf scroll work at the corners and at the middle of its sides and ends. Within the upper part of the border d, e, between it and the eagle are the words "Chargois' Elixir."

What I claim as my invention and desire to secure by Letters Patent is;

The design for trademark of "Chargois' Elixir" composed of the several diverse inscriptions and borders represented in the accompanying drawings and herein described.
